United States Patent Office

Des. 214,114
Patented May 6, 1969

214,114

BICYCLE HANDLEBAR

Norman A. Clarke, Westfield, Mass., assignor to The Columbia Manufacturing Co., Inc., Westfield, Mass., a corporation of Massachusetts

Filed Sept. 18, 1968, Ser. No. 13,592

Term of patent 7 years

Int. Cl. D12—11
U.S. Cl. D90—11

FIG. 3.

FIG. 4.

FIG. 5.

FIG. 1 is a perspective view of a bicycle handlebar showing my new design;

FIG. 2 is a top plan view;

FIG. 3 is a front view;

FIG. 4 is a bottom view;

FIG. 5 is a rear view thereof; and

FIGS. 6, 7 and 8 are cross sectional views taken on lines 6—6, 7—7, and 8—8, respectively, of FIG. 2.

The dotted line showing of the handlebar post and clamp is for illustrative purposes only.

I claim:

The ornamental design for a bicycle handlebar, as shown and described.
